UNITED STATES PATENT OFFICE

FRED J. BULLOCK, OF SHORTSVILLE, NEW YORK, ASSIGNOR TO PAPEC MACHINE COMPANY, OF SHORTSVILLE, NEW YORK, A CORPORATION OF NEW YORK

CUT-OFF VALVE FOR PIPES AND SPOUTS

Application filed May 19, 1930. Serial No. 453,570.

This invention pertains to cut-off valves suitable for use in pipes and spouts for conveying or delivering granular or pulverulent materials.

5 The object of the invention is to produce a simple and inexpensive structure, comprising only two pairs of parts, those of each pair being of identical form and dimensions, though differing from the parts of the other 10 pair. This reduces to two the number of patterns or dies, templates, etc., required for production of parts, and the number of different kinds of repair parts necessary to be kept in stock.

15 By providing two valve slides movable toward and from their meeting line at the mid-width of the central opening, the effective opening, when less than the possible maximum, will be somewhat distant from opposite 20 walls of the pipe or spout, thus permitting the material handled to fall practically clear of the interior surface of the pipe, and consequently lessening frictional contact therewith and tendency to lodge thereon and to 25 clog the pipe or spout.

The construction is such that one person can readily apply and remove the cut-off valve with the aid of a few simple tools, and in case of necessity, can do so with one hand, 30 assuming that bolts or tap screws be applied to the registering holes which connect the upper and lower plates.

The structure may be made of any suitable material, and may be of cast or sheet metal, 35 though in practice I prefer to use the latter because of rapidity, cheapness, and ease of production incident thereto.

The preferred embodiment of the invention is illustrated in the accompanying drawings, 40 wherein:

Fig. 1 is a perspective view showing the several parts of the structure slightly separated, better to disclose their form and relative arrangement;

45 Fig. 2, a longitudinal section through the structure and attached pipe sections as assembled; and

Fig. 3, a face elevation of the same with the end of the structure turned 90° from the position in which it is shown in Fig. 2.

Numerals 1 and 2 designate two identical members, here represented as plates of sheet metal of suitable gage and dimensions, each having one longitudinal edge portion turned over and laid upon the body of the plate, producing a raised rib or fold 4. Each of the plates 1 and 2 has a centrally located opening 3, of the form and dimensions of the interior of the pipe or spout for which the structure is designed, and near each longitudinal edge of the plate as folded, is a series of holes 5 to receive bolts, rivets, or other fastenings, four such holes being shown along each side edge. More or fewer may be provided, as found expedient. Each fold 4 has its free edge laid parallel with the longitudinal edges of its plate, and when one of the plates 1 or 2 is laid upon the other, with the ribs or folds 4 between them, the inner edges of the folds 55 constitute parallel guides for the valve plates 60 or slides 6 and 7. The ribs or folds 4 further serve as spacing elements to hold the bodies of plates 1 and 2 sufficiently apart to permit free movement of the valve plates or slides 65 70 75

Each of the plates 1 and 2 is further formed or provided with two lugs or ears 8 and 9 which, in the case of sheet metal plates, may conveniently be punched or cut from the plate by a suitable die or dies, and bent outward from but made substantially parallel with, the face of the plate, as seen in Figs. 1 and 2, the end of each lug remote from the central opening 3 being left integral with the plate as best seen in Fig. 2.

80 Metallic piping such as here contemplated and shown in the drawings, is usually made in sections of standard lengths, and these sections are quite commonly provided with radially flanged collars 10 at one or at both ends 85 where it is desired to make secure connection between proximate sections, the collars being made fast to the piping in any convenient or usual way. Such collared section or sections of piping will be provided wherever the cut-off or valve here described is to be used. It is for the purpose of positioning and at least temporarily holding a collar or collars in place against plates 1 and 2, or either 90 95 100 of them, that the lugs 8 and 9 are provided.

For the purpose of receiving bolts, rivets, or other fastenings by which to secure the cut-off to one or to two pipe sections, the radial flange 11 of each collar is provided with at least one hole 5^a on diametrically opposite sides, two being shown in the forward side of the upper collar in Fig. 1. The several holes 5^a are positioned to register with holes 5 of the plates 1 and 2, so that the fastenings may pass through corresponding holes in both plates, and one or both collars as one or more may be used.

It will be seen that by merely bringing one longitudinal edge of either plate 1 or 2 into contact with the exposed face of the proximate collar 10 and moving the plate laterally, the lugs 8 and 9 will be caused to pass over or under and to engage the flange of the collar, and draw and hold the face of the plate against the outer face of the collar. In this way the plate 1 or 2 will be held in proper position to receive the fastening bolts or rivets, and the proximate pipe sections (if two are being coupled) will be accurately alined.

The valve slides or plates 6 and 7 are exact duplicates, and each is preferably of six-sided form or outline, as seen in Fig. 1, with a downwardly turned lip 12 at the inner end, and a hand-hold 13 at the outer end, which may be turned either upward or downward. It is shown turned downward in the drawings. Each slide or plate is of a width to extend from the inner guiding edge of one fold 4 to the like edge of the opposite fold 4, with clearance sufficient to permit free movement of the plates or slides, but affording as little space as practicable for lodgement of material handled. The slides are maintained of uniform width from their inner ends to a point outward therefrom which will ensure a proper and complete covering of one-half of the central opening 3 of plates 1 and 2, but from such point they may be progressively narrowed to where the hand-hold 13 is formed, thus lightening the plate and avoiding waste of metal.

The several parts being constructed as above described, the lower plate 2 is placed in horizontal position, and the two valve plates or slides 6 and 7 are laid thereon with one edge of each against the guide ribs 4, 4, and advisably pushed inward to meet at the medial line of the opening 3. The upper plate 1 is then applied to and alined with the lower one, bringing its rib 4 into guiding relation to the proximate edges of valve plates or slides 6 and 7. Bolts are then inserted in the holes of one plate and passed through or screwed into the registering holes of the second plate, according as the bolts are provided with nuts or are screwed into holes of the second plate tapped to receive the tap bolts. If rivets, as 14, are applied instead of bolts, they will of course be headed at that end which is first passed through the holes.

As it is sometimes desirable to remove either the valve plates or slides 6 and 7 or the entire lower section of the valve holder formed by the plates 1 and 2, bolts may be used in preference to rivets. Bolts possess the advantage that they may be screwed into or out of the nuts or internally threaded holes by a simple screw driver held and manipulated by one hand, leaving the other hand of the workman free to shift belts, open or close a switch, set a rheostat, or perform like operations at the machine to which the pipe or spout is applied. If it be desired merely to remove the valve plates 6 and 7, the bolts may be backed off sufficiently to let the lower plate fall away from the upper plate a distance slightly in excess of the projection of the lugs 12 from the face of the slides, whereupon the slides may be drawn outward and lifted to carry the lugs clear of the central opening of the lower plate. If it be desired to remove the whole lower section of the valve guide or casing as well as the valve plates, the bolts may be completely freed from the nuts or the threaded holes 5, letting plate 2 down to any convenient stop or rest positioned to catch it.

To ensure free movement of the plates or slides 6 and 7 when the parts are assembled and secured together, said slides may be made of material of slightly thinner gage than the plates 1 and 2, or made initially of like gage and slightly ground on one face to give the necessary clearance.

The fastenings appearing in Fig. 2 are those located near the ends of plates 1 and 2, which lie outside the guiding edges of plates 6 and 7, as will be noted on reference to Fig. 3.

It is of course practicable to form the ribs 4 from separate strips of metal of proper length and width, laid upon or applied to the plates 1 and 2 or to both longitudinal edges of either plate, where they will be held by the bolts or fastenings passing through registering holes, as under the preferred construction above described. The folded form of plate avoids any slippage or displacement of the ribs in centering the parts, permits the holes of the rib and body of the plate to be simultaneously punched or drilled, and ensures perfect alinement of the holes of the body and rib. For these reasons, among others, the folded construction is deemed best.

Though designed primarily for use in pipes or spouts of so-called "roughage grinders", the device may be applied to pipes and delivery spouts generally, or in other words, is not restricted to any particular field.

I claim:—

1. A cut-off valve for pipes, comprising a frame or body composed of two identical plates, each of said plates provided with a longitudinal rib at one edge and with a central opening; two identical slides or valve members movable between the opposed faces

of the ribbed plates with their longitudinal edges lying between and guided by the ribs of the plates; and fastenings for securing the plates of the frame one to the other.

5 2. In combination with a radially flanged collar, a cut-off valve comprising two identical plates each provided along one longitudinal edge with a guiding rib projecting from its face and with a central opening registering with the collar; and a pair of identical slides movable between the opposed faces of said plates and between the ribs thereof, the collar flange and the plates being provided with registering holes to receive fastenings whereby the plates and the collars may be secured together.

10 3. In combination with two pipe sections each provided at one end with a radially flanged collar, a cut-off valve having a frame composed of two identical plates each having an opening registering with said pipes, and a rib projecting facewise from the plate along one longitudinal edge; two slides interposed between said plates and having their 15 longitudinal edges in proximity to the ribs of said plates; and fastenings passing through registering holes in the flanges of the collars and in the frame plates, and serving to unite said parts.

20 4. In combination with a radially flanged pipe collar, a cut-off valve comprising upper and lower frame plates each provided with an opening registering with the pipe, and having a longitudinal guiding rib near one 25 edge and lugs parallel with but set away from the outer face of the plate to overlap the collar flange; identical slides interposed between the frame plates and movable between the ribs thereof; and fastenings passing 30 through the collar flange and the frame plates, and serving to bind the same together.

35 5. In combination with a pair of pipe sections provided at their proximate ends with radially flanged collars, a cut-off valve comprising two frame plates provided on their faces each with a longitudinal rib and on their outer faces with lugs to overlie and engage the flange of the collar in contact with said faces; two slides interposed and movable between said frame plates and between the ribs thereof; and fastenings passing through the 40 collar flanges and through the frame plates and serving to bind the same together.

45 6. A cut-off valve for pipes and spouts, comprising a frame composed of two identical plates each having on one face a guiding rib; and a pair of slides placed and movable between the proximate faces of the frame plates and between the guiding ribs of the 50 respective plates, said slides being provided at their inner ends with projecting lips to limit their outward movement.

In testimony whereof I have signed my name to this specification.

60 FRED J. BULLOCK.
